UNITED STATES PATENT OFFICE.

HOWARD W. MATHESON, OF SHAWENEGAN FALLS, QUEBEC, CANADA.

PROCESS OF OXIDIZING MERCURY.

1,379,465.

Specification of Letters Patent. Patented May 24, 1921.

Application filed December 4, 1917. Serial No. 205,378.

To all whom it may concern:

Be it known that I, HOWARD W. MATHESON, a subject of the King of Great Britain, and resident of Shawenegan Falls, in the Province of Quebec and Dominion of Canada, have invented certain new and useful Improvements in Processes of Oxidizing Mercury, of which the following is a full, clear, and exact description.

10 This invention relates to improvements in process of oxidizing mercury, and the object of the invention is to provide a simple, safe and inexpensive process for producing mercuric oxid in a very pure state.

15 In my copending application, Ser. No. 204,008, which deals with the manufacture of acetaldehyde using mercuric oxid as a catalyst, it is stated that the sludge or waste product of the process is treated to reclaim

20 the mercury of the catalyst, and the reclaimed mercury then oxidized for re-use, so that in effect, practically none of the catalyst is lost, but simply goes through a process of decomposition into its original 25 elements and recombination of the reclaimed mercury with a fresh supply of oxygen to re-form the catalyst. In my copending application, Serial Number 205,379, the method of recovering the mercury from the

30 kettle sludge is dealt with. In this application, the process of combining the mercury with oxygen to form mercuric oxid is described. It will of course be understood that the process is not limited to the manufacture 35 of mercuric oxid solely for use in the manufacture of acetaldehyde, as the oxid may be used for any other purpose desired.

It has been found by experiment that 40 the oxidization can best be carried out electrolytically. According to the present invention, the mercury is oxidized by the passage of an electric current through a suitable alkaline or acid electrolyte, the oxygen 45 being furnished from the decomposition of the electrolyte, and the mercury itself serving as the anode. The current preferred is that of a low voltage and high amperage, this being found to be most suitable by experiment. Oxid, when formed on the surface 50 of the mercury, is removed by agitation of the electrolyte and drawn off in suspension in the electrolyte.

In greater detail, the process is as follows:—Mercury is placed to a depth of from half an inch to an inch in a suitable pan,

cell or receptacle, the mercury being insulated from the ground either by providing the receptacle with an insulating lining or by insulating the receptacle itself from the ground. A cathode of iron, nickel or other metal is provided above the mercury anode, electrically separate from the receptacle, and out of contact with the mercury. This cathode is apertured to permit the escape 60 of gas. The receptacle is then charged with a 3% to 10% solution of caustic soda, which acts as an electrolyte, and is of course in contact with both the anode and the cathode. A stirring device for the electrolyte is provided above the mercury, and is capable of rotating at any desired speed, the rotating means being preferably such that the stirrer may be moved slowly at the commencement 70 of the process and more rapidly at the end, 75 when the electrolyte is heavy with the oxid formed. One side of an electric circuit is connected to the mercury and the other to the cathode, and a current passed through having an amperage sufficient to give about 80 fifty-five amperes per square foot of anode surface exposed to the electrolyte, at a potential difference of eight to ten volts. The current specified is that preferred for a single cell, but if a number of cells are connected in series, the voltage on the terminals of the series will obviously be higher in proportion to the number of cells. It has been found advisable not to use series 85 requiring more than 200 volts, as with larger 90 series and consequently higher voltage, the danger to the operators and the difficulty of insulation is increased.

Oxygen is liberated on the surface of the mercury and oxidizes it to mercuric oxid. 95 Hydrogen is liberated at the cathode and escapes through the openings in the same. The stirrer is allowed to rotate slowly. As the oxidization proceeds, mercuric oxid forms on the surface of the mercury and the 100 stirrer rotating close to the surface serves to keep the mercury surface clean and allow the oxidization to continue. At the end of a half hour, a considerable amount of oxid has accumulated in the cell. The speed of 105 the stirrer is now changed to thoroughly mix this with the electrolyte, and the mercuric oxid in suspension in the electrolyte is drawn off near the base of the cell. Fresh electrolyte is then supplied, the speed of 110 the stirrers decreased and the reaction is continued. This procedure is continued in-

definitely, the mercury which has been oxidized being replaced, and the caustic soda solution, after sedimentation of the oxid, is returned to the cell.

5 It is necessary to provide means for drawing off the gases formed as the oxidization progresses.

The mercuric oxid in suspension in the electrolyte is drawn off from the cell periodically, as indicated above, and is run to suitable settling vats. Mercuric oxid is settled out in these vats by allowing the solution to stand for a few hours. The clear supernatant electrolyte is then drawn off to suitable storage vats and pumped back to the cells to be used over again.

10 A considerable amount of heat is given off by the passage of the current in the process outlined, and the electrolyte is drawn from the cells quite hot. After sedimentation of 20 the oxid, this electrolyte is cooled, by passing through a water condenser, before it is sent to the storage vats.

15 Mercuric oxid in the yellow modification is obtained by this process, and, as obtained in the settling tanks, it is mixed with a small amount of electrolyte solution. This oxid is washed once with water and then finally with dilute acid solution. It is then in a 30 suitable state to be used in the manufacture of acetaldehyde, according to my copending application, Serial No. 204,008.

25 If the mercuric oxid is to be used for any purpose other than the manufacture of acetaldehyde, it may be obtained in a very pure form by removal of the moisture.

30 The oxidization of the mercury may, according to the above described process, be carried out in a continuous manner. The 40 cells do not need to be operated until the mercury therein is all oxidized, but the mercury is recharged periodically to keep it at the same level in the bottom of the cell. When carrying on the process continuously, 45 as outlined above, a cell having approximately thirty square feet of mercury exposed will yield between eight and twelve pounds of mercuric oxid per hour.

35 In a preceding paragraph, it has been stated that the cell is provided with a stirring device and a cathode. These may be 50 separate elements, or a single moving element may be used serving both purposes, or the cathode may be mechanically but not necessarily electrically connected to the stirrer.

40 One form of apparatus suitable for carrying out the process is illustrated in section in the accompanying drawing. This apparatus 60 comprises a pan or suitable vessel 11 having a lining 12 of concrete or other insulating material. A metal anode 13 is

bedded in the lining 12 and is electrically separated from the vessel 11. A layer of mercury 14 is provided in the bottom of the 65 pan in contact with the anode and electrically speaking, forms a part of the anode. A cathode 15 is provided above the anode and is preferably in the form of spaced plates which will allow gas generated during 70 the re-action to escape between them. A stirring device 16 is provided in the cell in position to just clear the surface of the mercury. This stirring device is provided with mechanism 17 for driving it at two speeds. 75 As shown in the drawings the stirring device 16 is mechanically and electrically separated from the cathode but it is clear that this arrangement need not be adhered to. At one side of the vessel 11, and insulated 80 therefrom, is a mercury reservoir 18 having a valve controlled connection with the mercury in the cell. A valve controlled draw-off pipe 19 is provided leading from the cell a short distance above the level of the mercury.

85 Having thus described the invention, what is claimed is:—

1. A process of oxidizing mercury which comprises using metallic mercury as the 90 anode of an electrolytic cell in connection with a cathode formed of a metal of the iron family and a continuously agitated electrolyte, and periodically agitating the electrolyte with increased violence.

95 2. A process according to claim 1, in which the current employed in the cell is approximately fifty-five amperes per square foot of mercury exposed to the electrolyte at a potential difference of eight to ten volts.

100 3. A process according to claim 1, in which the electrolyte is agitated with increased violence as it becomes heavy with oxid, to maintain the surface of the mercury clear of oxid for continued electrolysis 105 and to enable the suspended oxid to be drained off from the cell.

110 4. A process of manufacturing an oxid of mercury, which comprises disposing mercury to be oxidized in an electrolytic cell and using the mercury as the anode of the cell in connection with a cathode formed of a metal of the iron family, and continuously agitating the electrolyte, and periodically increasing the violence of agitation when the 115 electrolyte becomes heavy with formed oxid to clear the surface of the mercury for further oxidation and to enable the oxid to be removed while in suspension in the electrolyte.

120 In witness whereof, I have hereunto set my hand.

HOWARD W. MATHESON.
